UNITED STATES PATENT OFFICE.

WALTER A. CHURCH, OF BINGHAMTON, NEW YORK, ASSIGNOR TO THE
BRISTOL BRASS & CLOCK COMPANY, OF BRISTOL, CONNECTICUT, A
CORPORATION OF CONNECTICUT.

SNAP-SWITCH.

SPECIFICATION forming part of Letters Patent No. 791,008, dated May 30, 1905.

Application filed October 18, 1902. Serial No. 127,818.

To all whom it may concern:

Be it known that I, WALTER A. CHURCH, a citizen of the United States, and a resident of Binghamton, in the county of Broome and State of New York, have invented certain new and useful Improvements in Snap-Switches, of which the following is a specification.

My invention relates to the class of devices used for making or breaking an electric circuit; and the object of my invention is to provide a device of this class having increased efficiency, in that an electric current of great power may be more safely and effectively carried than in prior devices of a like nature; and a further object is to provide a device of this class having simple and efficient means for connection to line-wires. A device in the use of which these objects may be attained is illustrated in the accompanying drawings, in which—

Figure 1 is a view in lengthwise section through the switch. Fig. 2 is a top or plan view with the cap removed. Fig. 3 is a detail perspective view illustrating the base of the switch cut in central section. Fig. 4 is a detail top view of the switch-plate. Fig. 5 is a detail perspective view of the same. Fig. 6 is a detail view, on enlarged scale, showing the stop-plate, cam-plate, spindle, and connected parts, the switch-plate being removed. Fig. 7 is a like view with the parts turned upside down. Fig. 8 is a detail view, on enlarged scale, showing one of the binding-posts with parts cut in section to show construction.

In the accompanying drawings the numeral 1 denotes the base of the switch, that may be made of porcelain or other convenient and desirable insulating material. This base is provided on opposite sides with recesses 2, in which binding-posts 3 for the line-wires are located, and also with oppositely-located sockets 4, to which the lamp or local wires are connected. The base has a central chamber 5, in which the switch-plate is located, and in the bottom of this chamber is a central recess 6, in which the mechanism for releasing the switch-plate is located.

The binding-posts 3 are composed of two

sections—a contact-section 7 and a wire section 8. The contact-section is cut away on one side, and the wire section rests in this cut-away portion. The contact-section projects into the central chamber with its upper surface preferably flush with the bottom of said chamber, and the depressed portion on which the wire section rests is located within the recess 2. This recess 2 is formed in the insulating material at one end of the central chamber 5, and when the contact-block 3 is in place a web of insulating material 3^a covers the inner face of the block and forms with the walls of the chamber a complete insulation for the several binding-posts and electrical connections.

Within a slot from the under surface of a binding-post a pivoted wire-clamp 9 is located, one arm of the clamp being operated upon by a clamp-screw 10 and the opposite end of the clamp projecting into the wire-socket 11 and arranged to clamp a wire between the clamp and the wall of the socket. This clamp is so arranged that as the screw is projected inward the clamp will be thrown out against the wire; but as the screw is turned out and a pull exerted on the wire the clamp will be released from its hold on the wire.

The description herein given for a single binding-post will be understood to apply equally to the binding-post located on the opposite side, this both as regards the binding-posts for the line-wires and also for the local or lamp wires.

The binding-posts for the local or lamp wires each consist of the binding-post 12 proper and a contact-piece 13, secured to the upper surface. This contact consists of a projecting piece bent and underlying the upper part of the contact and providing a spring-arm against which the contacts on the switch-plate rest.

A step-socket is located in the bottom of the central recess 6 and in which is located a step 14 for the bottom of the pin for operating the switch-plate. A stop-plate 15 is secured in the central recess 6, as by means of screws from the under side of the base. This stop-plate has several radial arms—four in the

form of switch herein shown—and these arms serve to stop and limit the movement of the switch-plate.

A spindle 16 has a broadened head 17 located in a recess in the under side of the stop-plate, and a releasing-pin 18 is secured to the spindle overlying the stop-plate 15.

A cam-plate 19 is mounted on the spindle, which passes through the central opening 10 therein, and the under surface of the cam-plate bears two stops 20, adapted to coöperate with the radial arms on the stop-plate to prevent forward movement of the switch-plate. One or both of these stops may also be arranged to co-15 operate with said radial arms to prevent backward movement of the switch-plate. The under surface of the cam-plate is also provided with a cam 21, upon which the releasing-pin 18 acts to lift the cam-plate to disengage the stop 20 from the radial arms on the stop-plate. This cam-plate also bears a shoulder 21^a to prevent, by contact of the releasing-pin 18 therewith, backward movement of the spindle 16. The upper surface of the cam-plate has an angularly-shaped head 22, adapted to receive an 25 opening of corresponding form in the switch-plate, and the stop is stepped, as shown, to allow the plate to gradually settle.

A collar 23 is secured to the spindle 16, and 30 a spring 24 has one end secured to the collar and its opposite end to the cam-plate 19.

The switch-plate 25 has an annular flange 26 projecting from the under surface into the space between the cam-plate 19 and the wall 35 of its recesses. This switch-plate is formed of porcelain or other desirable insulating material, and this flange projecting down into this recess effectually insulates the spindle and connected parts. The edge of the flange 40 covers the radial arms of the stop-plate, and the cam-plate is located in the recess formed by this annular flange 26.

Conductors 30 are located within a groove 45 in the switch-plate, this groove being then filled with a non-conducting substance, so that the conductors are practically located within the substance of the switch-plate. Each of these conductors terminates at each end in a switch-plate contact 27, the contact at one end 50 being located on top of the switch-plate and at the opposite end projecting from the bottom of the switch-plate, so that a current passing through the switch-plate passes in at one contact, through the conductor located 55 in the substance of the switch-plate, a quarter of the way therearound, and out at the contact located on the opposite surface of the switch-plate. The part exposed on the upper surface makes contact with the binding-post 60 contacts of the lamp or local wires and the part exposed on the bottom surface with the binding-post contacts of the line-wires.

A neck 29 projects upward from the switch-plate 25 to a point above the upper surface of 65 the base, this neck, together with the switch-

plate 25 and the annular flange 26, forming a sleeve inclosing the spindle and insulating it from any current passing through the switch. The stop-plate underlying the annular flange 26 is located well down in the recess and away 70 from the switch-plate contacts or the binding-posts, so that there is no liability of the electric current reaching said stop-plate. This construction protects the spindle from any liability of receiving any part of the electric 75 current. The binding-posts are all located well down in the recesses in the base, so that there is no danger of short-circuiting by contact of the metal cap 28 in placing it upon the base, and the construction therefore enables the switch to safely carry currents of 80 electricity of high voltage without danger of the current traveling any path other than that designed for it and without danger of shock to any one operating the switch. 85

While I have shown and described herein a form of device in which my invention may be embodied, I do not desire to limit myself to this exact form of construction, as it is obvious that it may be departed from to a considerable extent without departure from the invention, and any such departure from the construction will be understood as coming within the scope of the invention. 90

A cam 31 is provided with a hub 32, in opposite sides of which a spiral groove 33 is formed for the reception of a pin 34. This groove extends out through the bottom of the hub and provides not only for easy insertion and removal of the key, but also provides a means for preventing improper turning of the switch-spindle. It will of course be seen that unless the handle is turned so as to bring the pin 34 into the upper end of the spiral groove it will be impossible to turn the spindle. If a reverse movement should be given to the button, it would simply be turned off the spindle. 105

The operation of the device is as follows: Upon a rotation of the spindle 16 the spring 110 24 is put under tension and at the same time the pin 18, riding over the cam-surface 21, raises the cam-plate 19 until the stops 20 are lifted clear of the radial arms of the stop-plate 15. As the cam-plate 18 rises the angularly-shaped head 22 is raised into a correspondingly-shaped opening in the switch-plate 115 25 and rotates said switch-plate with its contact members under the influence of the spring 24 as soon as the stops 20 are disengaged from the arms 15. The cam-plate 19 rotates a quarter-turn, and the stops are then engaged with the next succeeding arms of the stop-plate 120 15.

An insulating-cap 35 may be placed on top of the base and surrounding the neck of the 125 switch-plate, as shown in Fig. 1 of the drawings.

What I claim as my invention, and desire to secure by Letters Patent, is—

1. A snap-switch including a base of insu- 130

lating material provided with a central insulated recess, binding-posts arranged within inclosed recesses formed in the walls of the central chamber and with their contacts located on the base, a switch-plate mounted on and fitting within the recess of the base and having contacts coöperating with those on the binding-posts said switch-plate having a sleeve extending from the bottom of the recess in the base to the top thereof, and a spindle located within said sleeve and operatively connected with the switch-plate.

2. A switch including a base having a central recess, binding-posts located within enclosed recesses in the base and with contacts only projecting therefrom, a switch-plate having a sleeve projecting from the bottom of the recess in the base to the bottom thereof, a spindle located in said sleeve and operatively connected with the switch-plate, and conductors located in the substance of the switch-plate and with the contacts only projecting therefrom in position to coöperate with the contacts on the binding-posts.

25 3. A switch including a base having a chamber and a central recess, binding-posts located in inclosed recesses in the base and having contacts only projecting therefrom, a stop-plate located in the recess, a cam-plate to co-
30 operate with the stop-plate, a spindle having a pin to coöperate with the cam, a switch-plate having a sleeve inclosing the spindle, the cam-plate and extending down into the recess, conductors located in the substance of the
35 switch-plate with the contacts only projecting therefrom, and means for operating the switch-plate.

4. In an electric switch in combination, a spindle, with appurtenant parts for operating the switch, a pin projecting from the spindle, and a key having a sleeve with an open-ended slot extending in a spiral direction from the edge of the key and adapted to receive said pin.

45 5. In combination in an electric switch having a spindle and coöperating parts, a pin projecting on opposite sides of the spindle, a key having a sleeve with a central opening for the reception of the spindle, and two oppositely - arranged open-ended slots extending in a spiral direction through the sleeve and adapted to receive the ends of said pin.

6. A switch including a base of insulating material with a central opening for the operating parts, a switch-body bearing contacts arranged within said depression, recesses formed in the side walls of the central depression and entirely inclosed and insulated from the central depression, binding-posts arranged in said recesses, and contacts projecting from the inclosed recesses into the central depression and coöperating with the contacts of the switch-body.

7. A switch-plate for a switch of disk form
65 having projecting necks on opposite sides of

the main portion of the disk, and a conductor comprising a pair of contacts located upon the flat surfaces of the disk and a part connecting the contacts and located within the substance of the switch-plate.

8. A switch-plate for a switch of disk form having on opposite sides thereof projecting necks, a plurality of conductors each of which includes two contacts located on the flat faces of the disk, and a connecting part extending through the substance of the switch-plate and connecting said contacts. 75

9. A switch-plate for a switch of disk form having projecting necks on opposite sides thereof, two conductors each including contacts one located on one flat surface and the other on the opposed flat surface of the disk, and a connecting part projecting from one of the contacts through the substance of the plate a portion of the way therearound and joining the opposite contact. 85 80

10. A snap-switch including a base of insulating material having a central depression providing a central insulated chamber, a switch-body arranged in said chamber and 90 provided with necks, means for rotating the switch - body said means extending therethrough and insulated from the central chamber by the necks, binding - posts arranged within recesses formed in the walls of the centrally-depressed chamber and having contacts projecting therefrom to engage contacts upon the switch-body said binding-post recesses being entirely insulated and isolated from the chamber of the switch-body. 95 100

11. A switch including a base of insulating material having a central insulated chamber, a cylindrical switch-body arranged within said chamber, contacts operatively arranged on the switch-body, recesses formed in the side walls of the centrally-depressed portion of the base and inclosed and insulated from said central recess, binding-posts arranged within said isolated recesses, contacts connected with the binding-posts and projecting into contacting positions with the switch-body and into the central chamber, and means for rotating the switch-body. 105 110

12. A switch-body including a base of insulating material having a central recess, one portion of said recess being of less diameter and extending below the main portion, a switch-body arranged to rest upon the ledge intermediate the recesses of varying diameters and with a neck projecting into the lower recess, a neck projecting from the opposite side of the switch-body, a stop-plate arranged in the bottom of the lower recess, connections intermediate said stop-plate and switch-body for causing movement of the latter to predetermined distances and an operating-spindle extending through the necks and stop-plate for actuating the parts. 115 120 125

13. A switch including a base of insulating material having a central insulated recess, a 130°

plate formed at the bottom of the recess, a spindle having a head located in a recess in said plate and a pin located on the opposite side of the plate, a cam-plate located on said 5 spindle and having a cam coöperating with the pin on the spindle, a spring secured to the spindle and to the cam-plate for imparting movement to the latter, a switch-body arranged to rotate with the cam-plate, said 10 switch-body being of cylindrical form and having protruding necks on opposite sides thereof, one of said necks extending into and closing the recess about the cam-plate and appurtenant parts and the other of said necks 15 inclosing the spindle and spindle-spring, and binding-posts and contacts appurtenant to the several parts.

14. A switch including a base of insulating material having a central insulated recess, a 20 stop-plate formed in the bottom of the recess and having radial arms, a spindle having a head located in a recess underneath the stop-plate and a pin overlying the stop-plate, a cam-plate located on the spindle and having a cam 25 coöperating with said pin, a spring connected with the spindle and with the cam-plate to impart movement to the latter, a switch-body

of tubular form having a neck projecting about the cam-plate and inclosing it within the lowermost part of the recess, and a second 30 neck projecting from the opposite side of the switch-body and surrounding and insulating the spindle and appurtenant parts, and contacts and binding-posts appurtenant to the several parts. 35

15. In a snap-switch, a base having concentric central depressions, recesses formed in the walls of the base about one of said depressions, binding-posts arranged within said recesses and provided with contacts projecting 40 into one of the central depressions, a switch-body of cylindrical form having the main portion of the body arranged in one of said recesses and with a neck projecting into and closing the second of said concentric recesses, 45 operating mechanism for said switch-body including a cam and stop-plate arranged within the switch-body and inclosed by the downwardly-projecting neck thereof.
